US00D892729S

(12) **United States Design Patent** (10) **Patent No.:** **US D892,729 S**
(45) **Date of Patent:** **** Aug. 11, 2020**

(54) **CHARGING STATION**

(71) Applicants: **Stefan Helnerus**, Arnsberg (DE);
Stefan Hillenmayer, München (DE)

(72) Inventors: **Stefan Helnerus**, Arnsberg (DE);
Stefan Hillenmayer, München (DE)

(73) Assignee: **innogy SE**, Essen (DE)

(**) Term: **15 Years**

(21) Appl. No.: **29/660,630**

(22) Filed: **Aug. 22, 2018**

Related U.S. Application Data

(62) Division of application No. 29/612,744, filed on Aug. 3, 2017, now abandoned.

(57) **CLAIM**

The ornamental design for a charging station, as shown and described.

DESCRIPTION

FIG. 1 is a perspective view of a charging station showing our new design;

FIG. 2 is a front view thereof;

FIG. 3 is a bottom view thereof;

FIG. 4 is a side view thereof;

FIG. 5 is a back view thereof;

FIG. 6 is a view of the side opposite to the side shown in FIG. 5;

FIG. 7 is a top view thereof; and,

FIG. 8 is another perspective view thereof.

1 Claim, 8 Drawing Sheets
